UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

NEGATIVE-RESISTANCE DEVICE.

Application filed July 5, 1919. Serial No. 308,852.

To all whom it may concern:

Be it known that I, ALBERT W. HULL, a citizen of the United States, residing at Schenectady, county of Schenectady, State of New York, have invented certain new and useful Improvements in Negative-Resistance Devices, of which the following is a specification.

My present invention relates to devices having negative resistance characteristics and more particularly to devices of this type which are adapted to be operated by means of electron currents flowing across an evacuated space.

One of the objects of my invention is to provide a negative resistance device which will be simple in construction and will be adapted to the various purposes to which such a device may be applied. A further and more specific object of my device is to provide an efficient form of amplifier for feeble electric currents.

The novel features which I believe to be characteristic of my invention are set forth with particularity in the appended claims, the invention itself, however, both as to its organization and method of operation together with further objects and advantages thereof will best be understood by reference to the following description taken in connection with the accompanying drawing in which Figs. 1 and 3 show in perspective two forms of my device, and Figs. 2 and 4 illustrate two other modifications partly in section and partly in perspective.

In all forms of my device illustrated an evacuated receptacle 1 is provided in which are sealed two electrodes 3 and 4, the electrode 4 being of filamentary form so that current may be passed through it for heating it to incandescence to cause it to emit electrons. In the form of my invention shown in Fig. 1, one of the leading-in conductors for electrode 4 has an extension thereon which is adapted to support one end of electrode 4 and which is interposed between electrodes 3 and 4 and forms a third electrode 8. The direct current source 5, which is connected to the leading-in conductors 6 and 7 for passing current through electrode 4, has its positive terminal connected to leading-in conductor 7 so that electrode 8 will be at a positive potential with respect to electrode 4. Electrode 3 has impressed thereon by means of the direct

current source 9 a potential which is positive with respect to that of leading-in conductor 6, but which is somewhat smaller than the potential of source 5. If the potentials of the two sources 5 and 9 are properly chosen and a variable potential is applied to the external circuit between electrodes 3 and 4, it will be found that the current in that circuit will vary over a certain operating range inversely as the potential applied to the circuit.

I have indicated in Fig. 1 one manner in which the device may be utilized as an amplifier. The current which is to be amplified is supplied to the circuit between electrodes 3 and 4 by means of a transformer 10. Included in this circuit is also a resistance 11 having positive resistance characteristics. If this resistance has a value of the same order of magnitude as the resistance of the evacuated space between the electrode 3 and the electrode 4, it will be found that potential variations will be set up across the terminals of resistance 11 of much greater magnitude than those applied to the circuit by transformer 10. These potential variations may be supplied by means of conductors 12 to any suitable device for obtaining an indication of the currents which are being amplified.

The device shown in Fig. 2 is similar to that shown in Fig. 1 with the exception that in this case the electrode 8 is made in the form of a spiral surrounding the heated portion 4. The electrode 3 is also made in the form of a cylinder surrounding the spiral electrode 8.

The operation of the devices of Figs. 1 and 2 whereby the result described is obtained, is substantially as follows:

Electrons emitted by the electrode 4 are attracted by the positive field set up by the electrode 8 and thereby given a high velocity. If the potential of electrode 3 is negative with respect to that of electrode 4 all of these electrons will either reach electrode 8 or return to electrode 4. If, however, the electrode 3 is positive with respect to electrode 4 some of the electrons emitted by electrode 4 will reach electrode 3 by reason of the high velocity given them by the positive field of electrode 8 and the attraction of the positive field produced by electrode 3. As the positive potential of electrode 3 is increased more and more elec-

trons will reach electrode 3 and the velocity with which they strike this electrode will also increase. When the potential is increased sufficiently these electrons will reach 5 electrode 3 with such velocity that they will be able by their impact to liberate secondary electrons which are attracted to the more positive electrode 8. As the positive potential applied to the electrode 3 increases a 10 point will be reached at which the number of secondary electrons emitted increases faster than the increase in the number of primary electrons reaching electrode 3. The current in the external circuit between electrodes 3 and 4 will then begin to decrease. 15 As the positive potential of electrode 3 is further increased a point may finally be reached at which each primary electron reaching electrode 3 will on the average 20 liberate one secondary electron which returns to electrode 8. Current in the external circuit will then be zero. A further increase in the positive potential of electrode 3 will cause the liberation of a greater number 25 of secondary electrons than the number of primary electrons received thereby. As a result the current in the external circuit will reverse in direction. This will continue until the positive potential of the electrode 3 approaches that of the electrode 8. The 30 current in the external circuit will then begin to approach the zero point and increase rapidly in the original direction. There will be a definite range of applied potentials to 35 electrode 3 over which the current in the external circuit varies inversely as the potential applied to that circuit, and the device when operated over this range is particularly adapted for use as an amplifier as well 40 as for various other purposes, as set forth in my U. S. Patents 1,313,187 and 1,313,188, of August 12, 1919.

In the devices shown in Figs. 3 and 4, the electrodes are arranged somewhat differently and the result is consequently brought about in a somewhat different way. In these cases the electrode 3 is interposed between the electrode 4 and the electrode 8. The electrode 3 has impressed thereon by means 45 of the battery 9, a potential which is preferably somewhat negative with respect to that of the electrode 4. In this case there will be a flow of electrons from electrode 4 to electrode 8. Since the electrode 3 is negative with respect to electrode 4 no electrons 50 will be received by electrode 3. If, however, the tube contains a small amount of gas the electrons passing from 4 to 8 will ionize this gas and the positive ions thus 55 produced will be attracted by the negative electrode 3 and produce a current in the external circuit between electrode 3 and electrode 4. The negative potential of electrode 60 3, however, restrains the free passage of 65 electrons between the electrodes 4 and 8,

and hence limits the number of electrons passing through the space and the number of positive ions produced. As the negative potential of the electrode 3 is decreased the flow of electrons between 4 and 8 increases, 70 the number of positive ions produced is increased, and hence the current flowing in the external circuit between electrodes 3 and 4 will increase, that is, the current in this circuit will vary inversely as the potential applied to the circuit. This action will continue until the potential of electrode 3 becomes substantially equal to or positive with respect to that of electrode 4. The electrode 3 will then be able to receive negative electrons and the current in the circuit between electrodes 3 and 4 will become zero and 80 reverse in direction because of the fact that it becomes a current carried by negative electrons instead of positive ions. This device, as indicated in Fig. 3, may also be used for purposes of amplification in the same manner as the device shown in Fig. 1. 85

The device shown in Fig. 4 differs from that shown in Fig. 3 only in the fact that 90 the electrode 8 is made in the form of a cylinder surrounding electrode 3.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims. 100

What I claim as new and desire to secure by Letters Patent of the United States, 105 is,—

1. An electron discharge device comprising an evacuated receptacle containing an electron emitting electrode and two cooperating electrodes to one of which one end of the electron emitting electrode is directly connected electrically within the receptacle. 110

2. An electron discharge device comprising an evacuated receptacle containing an electron emitting electrode and two cooperating electrodes, one of said cooperating electrodes constituting a portion of the connections by which current is supplied to the electron emitting electrode. 115

3. An electron discharge device comprising an evacuated receptacle containing an electron emitting electrode and two cooperating electrodes, one of said electrodes serving as a mechanical support for one end of the electron emitting electrode and constituting a portion of the connections by which current is supplied to the electron emitting electrode. 125

4. An electron discharge device compris- 130

ing an evacuated receptacle containing an electron emitting electrode and two cooperating electrodes, one of said electrodes being connected to a leading-in conductor and to 5 one end of the electron emitting electrode so as to form a part of the connections by which current is supplied to the electron emitting electrode.

5. An electron discharge device comprising an evacuated receptacle containing three electrodes, means for supplying current to one of said electrodes for heating it to incandescence, one of the other electrodes being so arranged that heating current for the 15 first electrode may be supplied therethrough, and means for producing a current between the heated electrode and the third electrode which varies inversely as the potential between said electrodes.

20. 6. An electron discharge device comprising an evacuated receptacle containing a filamentary electrode and two other cooperating electrodes, one end of said filamentary electrode being connected to one of 25 said other electrodes within the receptacle, and means for passing current through said filamentary electrode and the other electrode to which it is connected to heat said filamentary electrode to incandescence.

30. 7. An electron discharge device comprising an evacuated receptacle containing a filamentary electrode and two other cooperating electrodes, one end of said filamentary electrode being connected to one of 35 said other electrodes within the receptacle, means for passing current through said filamentary electrode and the other electrode to which it is connected to heat said filamentary electrode to incandescence, and means for 40 producing a current between said filamentary electrode and the third electrode which varies inversely as the potential between said electrodes.

8. An electron discharge device comprising an evacuated receptacle containing a filamentary cathode and two other cooperating electrodes, one end of said filamentary electrode being connected to and mechanically supported by one of said other electrodes, and means for passing current 45 through said filamentary electrode and the other electrode to which it is connected to heat said filamentary electrode to incandescence.

50. 9. An electron discharge device comprising an evacuated receptacle containing a filamentary cathode and two other cooperating electrodes, one end of said filamentary electrode being connected to and mechanically supported by one of said other electrodes, means for passing current through said filamentary electrode and the other electrode to which it is connected to heat said filamentary electrode to incandescence, and 55 means for producing a current between said

filamentary electrode and the third electrode which varies inversely as the potential between said electrodes.

10. A thermionic amplifier comprising an evacuated vessel containing a filamentary 70 electrode and two other cooperating electrodes, one end of said filamentary electrode being connected to one of the other electrodes within the receptacle, means for passing current through said filamentary electrode and the other electrode to which it is connected to heat said filamentary electrode to incandescence, an electrical circuit between said filamentary electrode and the third electrode, means for producing in said 80 circuit a current which varies inversely as the potential between said electrodes, means for applying potentials to be amplified to said circuit, and means for deriving from said circuit amplified potential variations 85 corresponding to those applied to the circuit.

11. An electron discharge device comprising an evacuated receptacle containing an electron emitting electrode and two cooperating electrodes, one of said cooperating electrodes being interposed between the other two and constituting a portion of the connections by which current is supplied to the 90 electron emitting electrode.

12. An electron discharge device comprising an evacuated receptacle containing an electron emitting electrode and two cooperating electrodes, one of said electrodes being interposed between the other two and being connected to a leading-in conductor and to one end of the electron emitting electrode so as to form a part of the connections by which current is supplied to the 100 electron emitting electrode.

13. An electron discharge device comprising an evacuated receptacle containing three electrodes, means for supplying current to one of said electrodes for heating it to incandescence, one of the other electrodes being so arranged that heating current for the first electrode may be supplied therethrough and means dependent upon gas ionization in the device for producing a current between the heated electrode and the third electrode which varies inversely as the 110 potential between said electrodes.

14. An electron discharge device comprising an evacuated receptacle containing three electrodes, a source of direct current for heating one of said electrodes to incandescence to cause it to emit electrons, one of the other electrodes being connected to the positive end of the electron emitting electrode within the receptacle so as to have produced thereon a positive electrostatic field for controlling the flow of electrons from the electron emitting electrode, and a source of current for maintaining the third electrode at a different potential from that of 120 125 130

- the second electrode, the voltages of the two sources being so chosen and the device being so constructed that a current will flow from the electron emitting electrode to the third electrode which will vary inversely as the potential between said electrodes.
15. An electron discharge device comprising an evacuated receptacle, an electron emitting electrode and two cooperating electrodes, leading-in conductors for supplying current to said electrodes, one of said cooperating electrodes being of spiral form interposed between the other two and having one point therein connected to a leading-in conductor and another point connected to the electron emitting electrode whereby it constitutes a portion of the connections by which current is supplied to the electron emitting electrode.
20. 16. An electron discharge device comprising an evacuated receptacle containing an electron emitting electrode, and two cooperating electrodes to one of which one end of the electron emitting electrode is directly connected electrically within the receptacle and one of said cooperating electrodes being in the form of a spiral conductor interposed between the other two electrodes.
20. 17. An electron discharge device comprising an evacuated receptacle, an electron emitting electrode and two cooperating electrodes and leading-in conductors for supplying current to said electrodes, one of said cooperating electrodes being of spiral form having one point therein connected to a leading-in conductor and another point connected to said electron emitting electrode

whereby it forms a portion of the connections by which current is supplied to the electron emitting electrode.

18. An electron discharge device comprising an evacuated receptacle, an electron emitting electrode and two cooperating electrodes, and leading-in conductors for supplying current to said electrodes, one of said electrodes having one point connected to a leading-in conductor and another point connected to one end of the electron emitting electrode, the opposite end of the electron emitting electrode being connected to a second leading-in conductor.

19. An electron discharge device comprising an evacuated receptacle, an electron emitting electrode and two cooperating electrodes, leading-in conductors for supplying current to said electrodes, one of said electrodes being of spiral form interposed between the other two and having one point connected to a leading-in conductor and another point connected to one end of the electron emitting electrode, the opposite end of the electron emitting electrode being connected to another leading-in conductor.

20. An electron discharge device comprising an electron emitting electrode, an electrode of spiral form surrounding said electron emitting electrode, and a third electrode surrounding said spiral electrode, said spiral electrode constituting a portion of the connections by which current is supplied to the electron emitting electrode.

In witness whereof, I have hereunto set my hand this 3rd day of July, 1919.

ALBERT W. HULL.
